UNITED STATES PATENT OFFICE.

MAUDE V. STANSBURY, OF AUBURN, NEW YORK.

BUST-GIRDLE.

1,063,399.

Specification of Letters Patent.

Patented June 3, 1913.

Application filed July 3, 1912. Serial No. 707,453.

To all whom it may concern:

Be it known that I, MAUDE V. STANSBURY, of Auburn, in the county of Cayuga, in the State of New York, have invented new and useful Improvements in Bust-Girdles, of which the following, taken in connection with the accompanying drawings, is a full, clear, and exact description.

This invention relates to certain improvements in bust girdles adapted to be adjustably fastened around the bust and held in place by suitable shoulder straps and having the front side thereof provided with pads to give fullness to the bust.

One of the objects is to provide a light, sanitary bust girdle of open lace work or netting which is cool and self-ventilating and adapted to be fitted closely to the form and at the same time to give more or less fullness to the bust.

Another object is to provide the front portions of the girdle with separate pockets for the reception of the pads or filling having self-closing open sides through which such filling may be inserted and removed at will, thus permitting the entire girdle and fillings to be thoroughly washed and laundered when desired.

Other objects and uses relating to specific parts of the girdle will be brought out in the following description:

In the drawings—Figure 1 is a perspective view of the girdle. Fig. 2 is an enlarged horizontal sectional view through one of the padded pockets and adjacent portions of the girdle taken on line 2—2, Fig. 1. Fig. 3 is an enlarged end face view of the open end of one of the pockets, partly in section, taken on line 3—3, Fig. 1. Fig. 4 is an enlarged horizontal sectional view through the rear laced ends of the girdle taken on line 4—4, Fig. 1.

This girdle preferably comprises opposite similar half sections —1— detachably united at their front ends by suitable fastening means as hooks and eyes —2— and having their rear ends adjustably connected by suitable lacing —3—, each half section being provided with a shoulder strap —4— having its ends attached to the upper edges of the front and rear portions thereof and its intermediate portions looped and adapted to be brought over and upon the shoulders to support the girdle in proper position around the bust.

The main bodies of the sections —1—

are preferably made of open lace work or netting —5— having their rear portions relatively narrow vertically but of substantially the same width and their front portions at opposite sides of the center somewhat enlarged or broadened vertically and provided with separable double layers of the lace work or netting —5— to form suitable pockets —6— for the reception of pads or fillings —7— preferably of the same material so as to reduce the weight and render these portions of the girdle cool and self-ventilating.

The upper and lower marginal edges of 70 the girdle sections —1— are finished with relatively narrow bindings —8— of somewhat stronger fabric than the lace work so as to give the girdle the desired form and allow it to be drawn tightly around the body 65 without liability of stretching or deforming the main body —1—. In like manner the front meeting ends of the girdle sections —1— are provided with relatively narrow binding strips —9— of the same material 75 as the bindings —8— and to which the hooks and eyes —2— are securely attached.

The rear meeting ends of the girdle sections —1— are also provided with binding strips —10— of the same material as the 80 binding strips —8— to which are attached loops —11— of similar material through which the lacing —3— is drawn, said binding strips —10— also forming hems for receiving vertical stays —12— of whale bone 90 or equivalent material to give the desired stiffness and form to this portion of the girdle at the center of the back.

For a similar purpose the portions of the girdle at the rear ends of the pockets —6— 95 and also the central portions of the front sides of the pockets are provided with vertical binding pieces —13— and —14— for receiving vertical stays —15— and —16— which preserve the predetermined form of 100 the marginal edges of the girdle, the binding strips —14— and stays —16— being located substantially midway between the vertical binding strips —9— and —13—.

The rear ends of the inner sides of the 105 pockets —6— are provided with separate vertical bindings —17— preferably of the same material as the bindings —13— having their ends attached to the adjacent portions of the lower and upper bindings —8— 110 and their intermediate portions separated therefrom to form an opening —18— into

the pocket —6— through which the fillings —7— may be inserted and removed.

5 Stays —19— of whale bone or equivalent material are also inserted in the bindings —17— and serve to automatically close the openings —18— by their own tension.

10 The fillings —7— are loosely inserted within their respective pockets —6— between the inner and outer sides —5— therefore and when made of open lace work or netting may be crumpled or folded to give the desired fullness without adding materially to the weight of the girdle or interfering with free ventilation therethrough, said fillings being removed when necessary through 15 the openings —18— to permit the parts of the entire girdle to be washed and laundered.

What I claim is:

A bust girdle composed of opposite half sections arranged end to end, means for connecting them at both their rear and front ends, a pocket formed on each of said sections by attaching thereto a piece of material upon three of its sides, a flexible strip 25 of material of substantially equal length with the width of said pockets attached to the free side of said pieces of material attached to form said pockets, and adapted to hold said pockets in closed position.

In witness whereof I have hereunto set my hand on this 26th day of June 1912.

MAUDE V. STANSBURY.
